UNITED STATES PATENT OFFICE.

ROBERT R. GIBBS, OF UTICA, NEW YORK.

DIE FOR CUTTING SOLES.

SPECIFICATION forming part of Letters Patent No. 518,596, dated April 24, 1894.

Application filed August 22, 1893. Serial No. 483,722. (No model.)

To all whom it may concern:

Be it known that I, ROBERT R. GIBBS, of Utica, in the county of Oneida, in the State of New York, have invented new and useful 5 Improvements in Dies for Cutting Soles, of which the following, taken in connection with the accompanying drawings, is a full, clear, and exact description.

My invention relates to dies for cutting soles 10 for boots or shoes, the cutters being adjustable laterally, to cut the different widths of each size direct from the race without first cutting out a sole blank and then trimming it to shape.

15 My object is to produce a sole-cutting die, constructed in sectional parts and comprising side cutters and toe and heel cutters, one or both of the side cutters being adjustable with relation to the toe and heel cutters so as 20 to adjust the die for cutting all of the widths of the sole of a given size direct from the race, ready for use without any trimming to shape the ends or sides, and thus accomplishing with one die and its adjustments, all that has 25 heretofore required a separate die for each size and each width of sole; said die being also adapted to cut insoles.

30 My invention consists in the several novel features of construction and operation hereinafter described and which is specifically set forth in the claims hereunto annexed. It is constructed as follows, reference being had to the accompanying drawings, in which—

Figure 1, is a top plan of the die. Fig. 2, is 35 a side elevation thereof. Fig. 3, is an end elevation thereof. Fig. 4, is a transverse vertical section on line X X in Fig. 2.

The body consists of two longitudinal sections —a and a'— the upper faces of which 40 are provided with dovetailed grooves which receive the tongues or tenons —b— of the plates —c and c'— said tongue and groove joints being the means for detachably mounting said plates upon said body sections. The side cutters or knives —d— are detachably 45 secured upon said plates, as by the screws shown in Fig. 4. The operation of these is to cut out the sides of the sole, or insole,

but as they, alone, would leave a connection between the race and the sole, I provide 50 the heel and toe cutters —e— to serve these connections, each of these cutters being secured to one side cutter by a screw —h— and to the other by the slot and screw —h'—; each heel and toe cutter overhanging inwardly 55 so as to overlap the ends of the side cutters and yet bring all of the cutting edges into proper alignment, so as to wholly sever the sole from the race.

The body sections —a— are bored transversely and suitably threaded to receive the screws —m—, said screws being each provided with the shoulders and grooves —n— and n' being a set screw inserted through the body, its point entering the groove. Each 65 of these adjusting screws is provided with a worm gear —r— and r'— is a shaft provided with worms —s— engaging said gears, and journaled in brackets —s'—.

Bars —t— connect the ends of the body sections, adjustably, by means of the slot and pin connection —t'— which are adapted to be loosened and then tightened after the cutters are adjusted to cut the width desired, such adjustment being effected by rotating the 75 shaft —r'—.

What I claim as my invention, and desire to secure by Letters Patent, is—

1. A cutting die comprising a longitudinally sectional body, plates removably mounted upon the sections, side cutters mounted upon said plates, heel and toe cutters connected to said side cutters, adjusting screws inserted through said body sections, and means to rotate said screws. 80

2. A cutting die comprising a longitudinally sectional body, side cutters mounted upon said sections, heel and toe cutters mounted upon and overlapping the side cutters, and means to adjust the body sections laterally. 90

In witness whereof I have hereunto set my hand on this 28th day of July, 1893.

ROBERT R. GIBBS.

In presence of—

ALBERT J. SEATON,
CHARLES H. HASTINGS.
